UNITED STATES PATENT OFFICE.

FRANKLIN G. HOBART, OF BELOIT, WISCONSIN, ASSIGNOR TO FAIRBANKS, MORSE & COMPANY, OF CHICAGO, ILLINOIS, A CORPORATION OF ILLINOIS.

GAS-PRODUCER.

No. 817,853.

Specification of Letters Patent.

Patented April 17, 1906.

Application filed April 19, 1905. Serial No. 258,415.

To all whom it may concern:

Be it known that I, FRANKLIN G. HOBART, a citizen of the United States, residing at Beloit, in the county of Rock and State of Wisconsin, have invented certain new and useful Improvements in Gas-Producers, of which the following is a specification, reference being had therein to the accompanying drawing.

The invention relates to new and useful improvements in suction gas-producers, and particularly in the construction of a vaporizer therefor.

It is essential to the successful operation of a suction gas-producer that the vaporizer should be sufficiently heated to produce a vapor of the requisite degree of saturation. To secure sufficient heat and at the same time locate the vaporizer where it will not interfere with the passage of the hot gases from the producer is the object of my invention.

My invention consists in the construction and arrangement of parts, as will be more fully hereinafter described, and set forth in the claims.

In the drawing I have shown a vertical section through the producer with the upper part of the magazine and the central part of the producer cut away.

A is what I shall call the "producer" and is preferably cylindrical and of the usual construction. As this is not embodied in my invention, I shall not further describe it. On this producer I attach the vaporizer B, preferably in the form of an annular casing forming the annular chamber C. Through one portion of the chamber passes the conduit D, leading to the scrubber or other part of the producer, and in the top of the chamber C is the air-inlet E and the water-inlet F. The top C' of the annular casing is preferably formed in a separate piece from and suitably attached to the casing. This top may be formed integral with the magazine K and may have the extension of the magazine formed integral or separate and attached, as clearly shown in the drawing.

In the top of the vaporizer-casing, and preferably at the opposite side from the inlets, I place the air and vapor outlet conduit G. This conduit passes down and enters the producer below the grate-bars H, and hence the suction through the producer will draw air and vapor from the vaporizer through the

conduit. By means of the check-valve G', pivoted at P in the conduit, I prevent the gas from passing back through the vaporizer whenever the pressure in the producer is above the atmospheric pressure, as in case of an explosion or when a blower is in operation in starting the producer. This check-valve consists simply of a plate G', hanging loose by gravity on a hinge or pivot P. The plate therefore offers little or no resistance to the passage of air or vapor, but closes immediately when a current of air starts back from the producer.

At the point of desired water-level in the vaporizer I attach the overflow-pipe I, which may be connected to the waste-pipe, and it is obvious that this overflow-pipe and the inlet and outlet conduits of the vaporizer may be connected thereto at any desired point without departing from the scope of my invention.

Above the vaporizer I arrange the magazine K of any desired form with an extension projecting substantially through the center of the annular casing and spaced therefrom, as clearly shown in the drawing. The inner side of the vaporizer-casing I provide with the ribs L, projecting into the space between the vaporizer and the extension of the magazine. The fuel is thus held away from the vaporizer by the extension of the magazine, and the intervening space is left free for the heated gas from the producer. The ribs L are thus in the path of this gas, while not obstructing its passage, and collect sufficient heat for a successful operation of the vaporizer. I have shown these ribs substantially vertical; but it is obvious that I may construct them in any desired form for collecting the heat.

The magazine may be of any of the forms known to those skilled in the art, and as this is not embodied in my invention I shall not further describe it. The extension of the magazine is preferably tubular and of the usual well-known funnel shape.

With the above-described construction the vaporizer and magazine form the top of the producer and may be attached thereto by bolts or by any other convenient means. The vaporizer is heated without obstructing the passage of the gas or the operation of the magazine. The volume of water in the vaporizer is kept uniform, and vapor containing

the requisite amount of moisture is constantly fed to the producer.

It is always found to be of great advantage and when using many fuels absolutely necessary to have means for agitating the fuel from above. On this account I have provided one or more poker-holes M at the top of the annular chamber surrounding the magazine, and in order to prevent the inlet of air or the outflow of gas I close the holes by some suitable device, such as the diametrically - perforated ball - valves N, as clearly shown in the drawing. By this location of the poker-holes a bar may be inserted to reach every part of the fire.

Having thus described my invention, what I desire to claim is—

1. In a gas-producer, the combination with a magazine, of an annular vaporizer surrounding the lower end of said magazine, and spaced therefrom, and a top for said vaporizer extending inwardly over the said space

and connected to said magazine, said top having apertures opening into said vaporizer, and valved poker-holes opening into the space between said magazine and vaporizer, for the purpose described. 25

2. In a gas-producer, the combination with a magazine, of an annular vaporizer surrounding the lower end of said magazine and 30 spaced therefrom, ribs on said vaporizer projecting into said space, and a top for said vaporizer bridging said space and connected to said magazine and having apertures opening into said vaporizer, and valved poker-holes opening into the space between said magazine and vaporizer, for the purpose described. 35

In testimony whereof I affix my signature in presence of two witnesses.

FRANKLIN G. HOBART.
